FRITZ LUBBERGER, OF BERLIN-SCHMARGENDORF, AND EDGAR HAHN, OF CHARLOT-
TENBURG, GERMANY, ASSIGNEES TO SIEMENS & HALSKE AKTIENGESELLSCHAFT,
WERNERWERK, OF SIEMENSSTADT, NEAR BERLIN, GERMANY.

AUTOMATIC TELEPHONE SYSTEM.

Application filed July 2, 1925, Serial No. 40,980, and in Germany July 18, 1924.

In the co-pending application of Lubberger Serial No. 41,034 filed July 2, 1925, of even date and its Figs. 1 to 3 is described and illustrated a method of setting up 5 incoming and outgoing calls in a telephone system comprising main and sub-exchanges arranged for automatic operation. The invention described in the said disclosure enables single and multiple metering to be effected 10 for such calls and enables a sub-exchange subscriber to be connected to the toll exchange. The invention also enables the local battery at the sub-exchange to be replaced by a source of current at the main 15 exchange, which provides the battery voltage for operating and holding the switching devices at the sub-exchange, this battery voltage being taken over one of the two speaking leads to the switching members at the sub-exchange. If the line resistance be high 20 owing to the great distance between the sub-exchange and the main exchange, and if furthermore relays, resistances, and choking coils be inserted in the lead, over which the 25 holding battery current is taken from the main to the sub-exchanges (in the above mentioned application this is taken over the speaking lead *b*), then the drop of potential 30 in the line may be so great that the voltage is insufficient to operate and to hold the switching members at the sub-exchange. The present invention removes this defect by using one special battery lead, which, in addition to the *a* and *b* speaking leads of the 35 individual trunk lines, connects the sub-exchange with the main exchange, and at the sub-exchange this special lead is connected by a relay to the individual battery leads of the switching members to be operated or 40 held.

With reference to the above mentioned application, a detailed description will be given hereafter of the switching operations for setting up an outgoing call from the subscriber *N* 300 of the sub-exchange when a relay *BA* is used for connecting up the battery, which relay functions when its circuit is closed.

The drawing shows in Figs. 1 and 2 by 50 way of example one circuit arrangement. When the subscriber *N* 300 originates a call, the following circuit is closed:

1. Earth, battery, back contacts *cf* 401 and

v 401, relay *R* 400, lead *bd* 103, choking coil *Dr* 100, back contacts *asp* 202 and *t* 302, 55 subscriber's station *N* 300, number dial contact *nu* 300, back contact *t* 304, relay *A* 300, earth.

The relay *R* 400 at the main exchange and the relay *A* 300 at the sub-exchange are 60 operated. The latter closes a double front contact *a* 301 in each trunk line; thereby an earth potential is applied to the battery connecting up relay of each trunk line. The relay *BA* 100 in the trunk line *VL I* is operated 65 in the following circuit:

2. Earth, battery, back contacts *cf* 401 and *v* 401, relay *R* 400, leads *bd* 103, choking coil *Dr* 100, relay *BA* 100, double front contact *a* 301, earth. 70

Thereby in each trunk line a contact *ba* 101 of the battery connecting up relay *BA* 100 connects the battery supply lead of the relays, one of which is associated with each trunk line (lead *batt* 101 in *VL I*), to the 75 battery supply lead *batt* 100, which is common to all trunk lines coming from the main exchange. The coupling relay *K* 100 of the first idle trunk line and the relay *C* 100 are 80 operated over:

3. Earth, double front contact *a* 301, relay *K* 100 winding *I*, lead *cd* 101, relay *C* 100 winding *I*, back contacts *d* 103, *zv* 103 and *asp* 201, battery supply lead *batt* 100. The relay *K* 100 closes the operating circuit for 85 the relay *t* 300 and closes the holding circuit for the relays *K* 100 and *C* 100 as follows:

4. Earth, relay *T* 300, winding *II* of relay *K* 100, front contact *k* 103, lead *dd* 101, 90 winding *II* of relay *C* 100, battery lead *batt* 101, front contact *ba* 101, battery supply lead *batt* 100.

The battery connecting up relay *BA* 100 of the trunk line *VL I* is locked over the 95 contact *c* 103 of the relay *C* 100, while the relay *T* 300 at its contacts *t* 301 and *t* 303 connects the calling subscriber through to the trunk line and marks him engaged to incoming calls by short circuiting the relay 100 *A* 300 at the front contact *t* 305. Thus the relay *BA* 100 of the trunk line taken into use is further maintained energized by the operation of the relay *C* 100 after the calling subscriber has been switched through. 105 At the same time the battery connecting

up relays BA of the other trunk lines are rendered operable by the subscriber's calling relay A 300, which has been de-energized after the back contact *t* 304 has been opened and it has been short circuited at the front contact *t* 305. The relays fall back and again disconnect the battery supply leads of the individual trunk lines from the battery supply lead *batt* 100.

12 The calling subscriber has now been connected through as far as the preselector associated with his trunk line at the main exchange:

15 5. Earth, battery, front contact *r* 401, relay R 500, back contact *t* 501, lead *ad* 103, back contact *l* 103, lead *ad* 101, front contacts *h* 101 and *t* 301, subscriber's station N 300, number dial contact *nu* 300, front contacts *t* 303 and *h* 102, lead *bd* 101, 20 relay B 100, earth.

25 The relay R 500 at the main exchange and the relay B 100 at the sub-exchange are operated. The relay R 500 thus starts up the preselector, which in known manner (see above mentioned application) hunts for an idle first group selector and connects through the leads *ad* 103 and *bd* 103 to the first group selector, the relays M 400 and V 400 being operated at the same time. The 30 operation of the relay B 100 causes the back contact *b* 103 to be once opened and at the front contact *b* 101 the relay D 100 is energized as follows:

35 6. Earth, front contact *b* 101, relay D 100, battery lead *batt* 101, front contact *ba* 101, battery supply lead *batt* 100.

Thereupon until the release of the connection, the relay D 100 locks itself over:

40 7. Earth, front contact *d* 101, relay D 100, battery lead *batt* 101, front contact *ba* 101, battery supply lead *batt* 100.

45 The front contact *d* 104 renders the second trunk line available for an incoming or outgoing call by connecting the battery supply lead *batt* 100 to the trunk line VL II over the back contacts *asp* 201 and *zv* 103, front contact *d* 104, back contact *d* II. The front contact *d* 102 prepares the metering circuit.

50 8. The further building up of the connection at the main exchange, the selecting operation and the switching through of the speaking leads to the wanted subscriber are described in the above mentioned application.

The release and metering after a successful call is effected in the following manner:

60 At the end of the conversation when the calling subscriber hangs up his receiver, the relay A 600 at the first group selector and the relay B 100 at the sub-exchange are released, as explained in the above mentioned application. Before the release takes place, metering impulses corresponding to

the operation of the multiple metering device are repeated over the *c* lead going from the first group selector to the preselector, to the metering relay ZR 500 at the preselector. The relay is operated in response to the impulses and at the contact *zr* 502 it earths the lead *ad* 103. Thereby the meter Z 300 receives metering impulses over the following circuit:

8. Earth, front contacts *zr* 502 and *t* 502, lead *ad* 103, back contact *l* 103, lead *ad* 101, front contact *d* 102, back contacts *zv* 101 and *b* 103, front contact *h* 104, meter Z 300, front contact *h* 105, battery lead *batt* 101, front contact *ba* 101, battery supply lead *batt* 100.

Metering having ended, the first group selector releases; relay M 400 falls back and at contact *m* 403 it interrupts the circuit of relay V 400, which falls back after some time as it is very slow acting.

Thus during the time taken by the relay V 400 to release, the battery is disconnected from the lead *bd* 103. The relays R 400 and BA 100 fall back; the relay BA 100 at its contact *ba* 101 opens the battery lead *batt* 101 for the relays of trunk line VL I. The relays C 100 winding II, K 100 winding II, D 100 and T 300 fall back.

For calls from the main exchange to a 95 subscriber N 300 of the sub-exchange the calling relay AR 100 of the trunk line is energized after the preselector belonging to a trunk line going to the sub-exchange has been taken into use from the second group 100 selector over the leads *ad* 103 and *ad* 101 (see aforementioned application). At its contact *ar* 104 the relay AR 100 connects up the battery connecting up relay BA 100.

9. Earth, battery, back contact *of* 401, 105 front contact *m* 401, relay R 400, leads *bd* 103 and *bd* 101, choking coil Dr 100, relay BA 100, front contact *ar* 104, earth.

The relay BA 100 is operated and at its contact *ba* 101 it connects the battery lead *batt* 101 with the battery supply lead *batt* 100. Furthermore the relay ZV 100 is operated as follows:

10. Earth, front contact *ar* 101, relay ZV 100, battery lead *batt* 101, front contact *ba* 101, battery supply lead *batt* 100. At its double front contact *zv* 102 the relay closes a holding circuit for itself and a holding circuit for the relay BA 100. The contact *zv* 101 opens the lead *zd* 101, hence the meter Z 300 cannot operate. The contact *zv* 104 renders the trunk line VL II available over:

11. Battery supply lead *batt* 100, back contact *asp* 201, front contact *zv* 104, back contact *d* II, lead *ad* 102 of the trunk line VL II. The selection of the subscriber N 300 of the sub-exchange takes place in the same manner as that described in the aforementioned application.

If the wanted subscriber is free, the call- 130

ing relay A 300 associated with his line is energized over the exciting circuit:

12. Battery supply lead *batt* 100, front contact *ba* 101, battery lead *batt* 101, front contact *m* 202, relay F 200, front contact *i* 32, relay A 300, earth. The latter closes its double front contacts *a* 301, etc., in all the trunk lines VL, and thus causes the relays C 100 and L 100 to operate in the trunk line

10 VL I over the following circuit:

13. Earth, double front contact *a* 301, relay K 100 winding I, lead *cd* 101, relay C 100 winding I, front contact *m* 201, relay L 100, battery lead *batt* 101, front contact *ba* 101, battery supply lead *batt* 100. The relays K and C in the other trunk lines VL cannot operate, because the relays ASp 200 and M 200 have been operated at the end of the selection, as shown in the aforementioned application. The relay L 100 locks over:

14. Battery supply lead *batt* 100, front contact *ba* 101, battery lead *batt* 101, relay L 100, front contact *l* 102, resistance *WL* 100, back contact *b* 102, earth, and connects at its front contact *l* 104 the lead *ad* 101 to the source of ringing current. The relay K 100 closes the following circuit, in which it as well as the relay C 100 is locked and the relay T 300 is energized.

15. Earth, relay T 300, relay K 100 winding II, front contact *k* 103, lead *dd* 101, relay C 100 winding II, battery lead *batt* 101, front contact *ba* 101, battery supply lead *batt* 100.

The relay C 100 at its contact *c* 101 disconnects the earth potential from the calling relay of the trunk line VL I. The relay AR 100 falls back. The relay T 300 at its front contacts *t* 301 and *t* 303 connects the wanted subscriber N 300 to the speaking leads *ad* 101 and *bd* 101, hence the subscriber is now called over the following circuit:

16. Earth, battery, source of ringing current, front contact *l* 104, lead *ad* 101, front contacts *k* 101 and *t* 301, subscriber's station N 300, number dial contact *nu* 300, front contacts *t* 303 and *k* 102, lead *bd* 101, relay B 100, earth. The relay B 100 does not respond to alternating current. When the wanted subscriber answers, battery current flows over the last mentioned circuit and the relay B 100 is operated. At its front contact *b* 102 it disconnects the holding circuit of the ringing relay L 100 and at its front contact *b* 101 it connects up the relay D 100. The relay L 100 releases and at its contact *l* 103 it closes the *a* lead *ad* 101, so that the speaking route is now closed between the two subscribers.

At the end of the conversation, when a subscriber hangs up his receiver, it will be seen from Fig. 3 of the aforementioned application that the relay M 400 at the pre-selector VW is deenergized, the relay re-

leases and disconnects the battery from the lead *bd* 103, because the relay V 400 releases its armature slowly. At the same time the relays R 400 and BA 100 return to their normal position. The relay BA 100 at its front contact *ba* 101 opens the battery lead *batt* 101, so that the relays C 100 winding II, K 100 winding II, T 300, D 100, ZV 100 now release.

If the wanted subscriber N 300 be engaged 75 when a call arrives from the main exchange, the relay F 200 is energized in the following circuit at the end of the numerical selection.

17. Battery supply lead *batt* 100, front contact *ba* 101, battery lead *batt* 101, front contact *m* 202, relay F 200, front contacts *i* 32 and *t* 305, earth. The relay F 200 connects up the busy tone relay BR 100 over:

18. Earth, back contact *l* 101, front contact *f* 201, relay BR 100 winding I, battery lead *batt* 101, front contact *ba* 101, battery supply lead *batt* 100. The busy tone relay BR 100 locks itself over the *a* speaking lead (battery at the lead *ad* 401 at the second group selector, pre-selector wiper VW *a*), see the aforementioned application, and thence over:

19. Back contact *sr* 501, front contact *t* 502, lead *ad* 103, back contact *l* 103, lead *ad* 101, back contact *c* 101, front contact *br* 102, relay BR 100 winding II, earth. 95

At its contact *br* 101, the relay BR 100 disconnects the calling relay AR 100 from the lead *ad* 101. The relay AR 100 is deenergized and opens its contact *ar* 104. The battery connecting up relay BA 100 is maintained energized over the contact *zv* 102 until the release. The calling subscriber is given the busy tone over an induction coil winding on the relay BR 100 and the lead *ad* 101 and *ad* 103. Upon the release, the relays M 400 and V 400 at the main exchange and the relay BA 100 at the sub-exchange are deenergized. Upon releasing, the relay BA 100 opens the battery lead *batt* 101, hence the relay ZV 100 falls back. 105

If the sub-exchange be provided with a battery connecting up relay (BA 100) operated by current normally flowing over the line from the main exchange, the circuit changes are similar to those above described for incoming and outgoing calls to and from the sub-exchange. (Fig. 2.) 115

Normally the relay BA 100 is energized as follows:

20. Earth, battery, back contacts *cf* 401 and *v* 401, relay R 400, lead *bd* 103, choking coil *Dr* 100, relay BA 100, earth. 120

Thus the battery lead *batt* 101 of the trunk line VL I is normally connected to the common battery supply lead *batt* 100 by the contact *ba* 101. Hence the relay R 400 at the main exchange is not energized over the high resistance winding of the relay BA 100, and it only operates when upon a subscriber of the sub-exchange (N 300) being 125

called, the calling relay A 300 belonging to this subscriber is connected in shunt to the relay BA 100.

By a call of the subscriber N 300 of the sub-exchange, the relay R 400 at the main exchange and relay A 300 at the sub-exchange are operated as above described. The latter at its contact *a* 301 closes the primary circuit of the individual trunk lines, hence 10 the first idle trunk line VL can be taken into use as follows:

21. Earth, front contact *a* 301, relay K 100 winding I, lead *cd* 101, relay C 100 winding I, back contacts *d* 103, *zv* 103 and *asp* 15 201, battery supply lead *batt* 100. The further circuit changes and switching through 20 operations, as well as the selecting, take place in the manner above mentioned. The release is effected after the conversation has 25 ended and the metering operation has been completed; this entails as before the de-energization of the relays M 400, V 400 at the main exchange. During the time taken by the relay V 400 to release slowly, the lead 30 *bd* 103 loses its voltage, the relay BA 100 at the sub-exchange now falls back and interrupts the battery supply lead *batt* 101 of the holding relays at the sub-exchange, hence the relays can return to their normal position.

Since the relay BA 100 is normally energized, battery voltage is applied to the battery supply lead of the switching relay of each trunk line VL when a call is made from the main exchange to the sub-exchange. Only when release takes place, is battery disconnected from the lead *bd* 103 by the contacts *m* 401 and *v* 401 at the main exchange; thereby the relay BA 100 and the holding relay at the sub-exchange release as before.

What is claimed is:

1. In an automatic telephone system, a main and a sub-exchange, a group of trunks between said exchanges, a source of current at said main exchange, a single battery conductor between said exchanges, automatic switching equipment in said exchanges, subscribers' lines terminating in said exchanges, means controlled by a calling subscriber for extending a talking connection between the main and sub-exchange over one of the trunks of said group, the current for positioning and controlling said sub-exchange automatic switching equipment being received from said main exchange source over said battery conductor and selected trunk respectively.

2. In a telephone system, a main and a sub-exchange, a group of trunks between said exchanges, said group comprising a plurality of talking conductors and a battery supply conductor, switching equipment in the sub-exchange, a battery control relay in the sub-exchange associated with each of said trunks,

and means for operating said relay from the main exchange battery over the associated trunk, said relay operating to connect the switching equipment associated with the selected trunk with said battery supply conductor.

3. In a telephone system, a main and a sub-exchange, a group of trunks between said exchanges, said group comprising talking conductors and a battery supply conductor, switching equipment in said exchanges, a source of current at said main exchange, a battery control relay in said sub-exchange, subscribers' lines terminating in said exchanges, means responsive to the removal of the receiver from one of said sub-exchange subscribers' lines for energizing said battery control relay by current received from said main exchange source, means for operating part of said sub-exchange switching equipment to associate said calling line with an idle one of said trunk lines, and means at the main exchange for controlling the release of said operated equipment independent of said calling line.

4. In a telephone system, a main and a sub-exchange, a group of trunks between said exchanges, a source of current at said main exchange, a battery conductor between said exchanges, switching equipment in said exchanges, subscribers' lines terminating in said exchanges, a relay associated with each of the trunks of said group arranged to connect that part of said switching equipment associated with that trunk to the battery conductor, means responsive to the initiation of a call by one of said sub-exchange subscribers for energizing all of said relays, means for selecting one of said trunks, and means for releasing all of said relays except the one associated with said selected trunk.

5. In an automatic telephone system, a main and a sub-exchange, a plurality of trunks between said exchanges, a source of current at said main exchange, a battery conductor common to said trunks between said exchanges, switching equipment in said exchanges, a relay at said sub-exchange associated with each of said trunks, contacts in said battery conductor controlled by said relay, and means responsive to the initiation of a call over one of said trunks for energizing said relay by current from said main exchange source, said relay closing said contacts to connect said sub-exchange switching equipment with said battery conductor.

In witness whereof, I hereunto subscribe my name this 12th day of June, A. D. 1925.

FRITZ LUBBERGER.

In witness whereof, I hereunto subscribe my name this 12th day of June, A. D. 1925.

EDGAR HAHN.
